UNITED STATES PATENT OFFICE.

LOUIS N. D. WILLIAMS, OF OGONTZ, PENNSYLVANIA.

STITCH TRANSFERRING AND UNITING DEVICE.

1,191,642.

Specification of Letters Patent. Patented July 18, 1916.

Application filed August 6, 1915. Serial No. 43,959.

To all whom it may concern:

Be it known that I, LOUIS N. D. WILLIAMS, a citizen of the United States, residing in Ogontz, Pennsylvania, have invented 5 certain Improvements in Stitch Transferring and Uniting Devices, of which the following is a specification.

My invention relates to a method of uniting knitted webs which consists in first 10 engaging two sets of stitch receiving quills or points (hereinafter, for convenience, termed "points") with the stitches to be united, then adjusting each set of points, with the stitches upon them, into close relation to the other 15 set, and then uniting the stitches carried by the two sets of points by means of a chain of stitches, while the stitches to be united are still upon the original transfer points, the object of my invention being to permit 20 of the ready disengagement of the points and stitches after the webs have been united.

This object I attain in the manner herein-after set forth, reference being had to the accompanying drawing, in which—

Figure 1 is a sectional view of part of a circular knitting machine and of a device in accordance with my invention for engaging stitches of the knitted web, said device being in position to engage said stitches; 25 Fig. 2 is a sectional view illustrating the members of the stitch receiving device in position for bringing the engaged stitches into close relation for the action of the looping device whereby the uniting chain of stitches is produced; Fig. 3 is a similar view illustrating a change in the position of the stitch receiving points in respect to their carriers in order to permit of the removal of the united webs from said points or the points 30 from the webs; Fig. 4 is an under face view of the stitch engaging device when the parts of the same are in the position shown in Fig. 1; Fig. 5 is a view similar to Fig. 1 but showing points which engage the stitches 35 from below the web instead of from above the same; Fig. 6 is a sectional view showing the stitch engaging device of Fig. 5 removed from the machine and partially folded, and Fig. 7 is a view showing the point carriers 40 folded back to back as in Fig. 2, for the action of the looping machine for uniting the stitches upon the points.

In the drawing, I have shown only the diametrically opposite wales of the webs and 45 the points which engage them, as the show-

ing of the intermediate wales and points would only cause confusion.

The stitch receiving device may, in case of a circular web, consist of two semi-circular segments 1 and 2 each provided with a segmental series of stitch engaging points, pivoted thereto, each point comprising two members 1^a and 1^b, or 2^a and 2^b, respectively, each extending from the pivotal axis of the point in a direction substantially at a right angle to that of the other. The segments are notched as at 1^c or 2^c for the reception of the member 1^b or 2^b of each point so that the members 1^a and 2^a may be caused to project in planes at right angles to the faces 60 of the segments 1 and 2, as shown in Figs. 1 and 2, or may be permitted to swing into planes substantially parallel with said faces, as shown in Fig. 3.

When the members 1^a and 2^a of the points 75 occupy the positions shown in Figs. 1 and 2 the members 1^b and 2^b are contained within the slots 1^c, 2^c, of the segments and are locked therein by engagement with the fingers 3^a of segments 3, slidably mounted 80 upon the faces of the segments 1 and 2, as shown in Fig. 4, and provided with notches 3^b which are moved into line with the members 1^b or 2^b of the points when it is desired 85 to permit the latter to swing from the position shown in Fig. 2 to that shown in Fig. 3. When the points are in the latter position they may be locked in such position, if desired, by engagement of the upper faces of the fingers 3^a with the backs of the members 90 1^b or 2^b of the points.

When the parts are in the position shown in Fig. 2, the terminal stitches of the opposite portions of the knitted web are in position to be united by a chain of stitches α 95 produced by the looping mechanism of an ordinary looping machine, as shown by dotted lines in Fig. 2, the swinging needle of said looping machine engaging in succession the pairs of terminal stitches of the web from one end of the segments to the other. If, however, the points were permanently fixed in the position shown in Fig. 2, these connecting stitches α would prevent 100 the removal of the terminal stitches of the web from said points, or the points from the stitches, as removal would have to be in the direction of the arrows, Fig. 2. When, however, the points are permitted to swing, 105 as shown in Fig. 3, so as to occupy the same 110

plane as the segments 1 and 2 the stitches can be withdrawn from the points or the points from the stitches in the direction of the arrows Fig. 3, and the connecting 5 stitches a present no obstacle to such movement.

The stitch receiving device shown in Fig. 1 is intended for application to the knitted web from above the same but the stitch 10 engaging device may be mounted within the knitting machine, and, after the completion of the web upon the needles of the machine can be projected so as to engage the 15 stitches on the needles, or the stitches of a previous course, from below the web, as shown in Fig. 5.

After the stitch engaging points, with the web upon them, have been removed from the machine, the segments may be folded, 20 as shown in Fig. 7, so as to bring them back to back and dispose the terminal stitches of the web or webs close enough together to permit them to be united by the chain of 25 stitches formed by the looping machine, and when the segments have been folded to such position that the strain upon the web will not tend to pull the stitches from the members 1^a or 2^a of the points, the web may be 30 withdrawn from between the segments, as shown by dotted lines in Fig. 6, in order to permit said segments to be adjusted back to back, as shown in Fig. 7.

Although I have described my invention as applied to the uniting of stitches around 35 the opposite halves of a tubular web it will be evident that it can, with equal advantage, be employed in uniting the terminal stitches of two flat webs produced upon two straight needle beds, or two flat webs produced by reciprocating knitting upon opposite semi-circular sets of needles.

I claim:-

1. In a device for uniting knitted webs, 40 two sets of stitch engaging points, a two-part carrier to which said points are pivoted so as to be capable of changing their angle of projection therefrom, said parts of the point carrier being adjustable in respect to one another so as to lie in the same 45 plane, with the points of one set separated from those of the other set, or so as to overlap one another with the points butt to butt, in combination with looping mechanism 50 whereby the stitches upon corresponding pairs of points can be united when said points are adjusted butt to butt.

2. In a device for uniting knitted webs, 55 two sets of stitch engaging points, a two-part carrier to which said points are pivoted so as to be capable of changing their angle of projection therefrom, and means 60 for temporarily locking said points to said carrier in one of their positions of adjust-

ment in respect thereto, said parts of the point carrier being adjustable in respect 65 to one another so as to lie in the same plane, with the points of one set separated from those of the other set, or so as to overlap one another with the points butt to butt, in combination with looping mechanism 70 whereby the stitches upon corresponding pairs of points can be united when said points are adjusted butt to butt.

3. In a device for uniting knitted webs, 75 a plurality of web carriers each having a stitch engaging points pivotally mounted thereon so as to assume positions substantially at a right angle to one another, said web carriers being also adjustable in respect to one another so as to cause all of the stitch engaging points to project in the same direction or those of one carrier to project in a direction opposite to those of the other carrier.

4. In a device for uniting knitted webs, 80 a web carrier having pivotally mounted thereon a series of stitch engaging points each comprising two members one at a right angle or thereabout to the other, and means mounted upon said carrier and movable into and out of engagement with one of said point members in order to lock the stitch engaging members in position or release the same.

5. In a device for uniting knitted webs, 85 a web carrier having pivotally mounted thereon a series of stitch engaging points each comprising two members one at a right angle or thereabout to the other, said carrier being slotted for the reception of one 90 of said point members.

6. In a device for uniting knitted webs, 100 a web carrier having pivotally mounted thereon a series of stitch engaging points each comprising two members one at a right angle or thereabout to the other, said carrier being slotted for the reception of one of said point members, and means for locking the latter members in said slots.

7. In a device for uniting knitted webs, 105 a web carrier having pivotally mounted thereon a series of stitch receiving points each comprising two members one at a right angle or thereabout to the other, and means 110 engaging one of said point members in order to lock the stitch engaging members in position, said means comprising a sliding plate with notched outer edge.

In testimony whereof, I have signed my name to this specification, in the presence 115 of two subscribing witnesses.

LOUIS N. D. WILLIAMS.
